SHANK STIFFENER MACHINE

Filed July 9, 1925

2 Sheets-Sheet 2

UNITED STATES PATENT OFFICE.

WILLIAM H. NICKERSON, OF BROOKLINE, MASSACHUSETTS.

SHANK-STIFFENER MACHINE.

Application filed July 9, 1925. Serial No. 42,454.

This invention relates to mechanism for forming shoe-shank stiffeners from a strip of sheet metal of indeterminate length.

The invention is embodied in the improvements hereinafter described.

Of the accompanying drawings forming a part of this specification,—

Figure 1 is a top plan view of the fixed base portion of my improved mechanism and the parts carried thereby.

Figure 2 is a section on the plane of line 2—2 of Figure 1, showing in section the reciprocating head and the parts carried thereby.

Figure 3 is a bottom plan view of the head and the parts carried thereby.

Figure 4 is a section on line 4—4 of Figure 2.

Figure 5 is a section on line 5—5 of Figure 2.

Figure 6 is an isometric view, showing the reciprocating and fixed punch dies, the bending block and the presser hereinafter described, and a portion of a strip which has been acted on by said parts.

Figure 7 shows a horizontal section of the reciprocating punch dies, and by dotted lines a portion of the strip.

Figure 8 is a perspective view of a stiffener formed by my improved mechanism.

Figure 9 is a fragmentary perspective view, showing the reciprocating punch die.

Figure 10 is a fragmentary perspective view, showing the fixed punch die.

Figure 11 is a section on line 11—11 of Figure 9.

Figure 12 is a section on line 12—12 of Figure 10.

The same reference characters indicate the same parts in all of the figures.

12 designates a base fixed to a press bed 13, and secured thereto by screws 11 (Figure 4). Fixed by screws 14 (Figure 2) to the base plate is a lower forming die 15, having a curved longitudinal embossing rib 16, and curved forming faces 17, at opposite sides of the rib. 18 designates a movable upper forming die, having a curved longitudinal groove 19, and curved forming

faces 20, at opposite sides of the groove. The upper die is fixed by screws 21 to a head 22, which is secured by screws 23 to a vertically reciprocating member 24 of a press.

The forming elements 16 and 17 of the lower die have a reentrant curvature, and the elements 19 and 20 of the upper die have a

salient curvature, the dies being adapted to form, on a sheet metal strip interposed between them, the curved portion having the curved rib 25, and the lateral flanges 26 shown by Figure 8. The dies 15 and 18 have flat end faces, which contact with portions of the strip, so that the flat tab-forming portions 27 are left on the strip from which the prongs 28 and tabs 29 are formed by punching and bending dies, as herein-after described.

The strip is fed into the machine in the direction of arrow α (Figure 2), and is held at rest while the portions 25, 26 and 27 are being formed by the forming dies. The base 12 and the head 22 are elongated, as shown by Figures 1, 2 and 3, to project from the forming dies and provide a space for the reception of grippers 30 and 31, adapted to grip the portion of a strip which has been formed by the dies 15 and 18, and moved lengthwise from between said dies.

The lower gripper 30 is provided with a rib 32 (Figure 1), adapted to enter the strip rib 25, and the upper gripper 31 is provided with a groove 33 (Figure 3) adapted to receive the strip rib. The lower gripper 30 is vertically movable, and is yieldingly supported in the position shown by Figure

2, by springs 34 surrounding headed studs 35, whose heads are movable in sockets 36, in the base 12, and are limited in their upward movement by shoulders at the upper ends of the sockets. The portion of the

head 22, projecting from the upper forming die 18, is provided with guides 38, in which steady pins 39, fixed to the upper gripper 31, are vertically movable. The gripper 31 is pressed downward by a spring 40, surrounding a headed stud 41, fixed to the gripper, the head of the stud being movable in a socket 42 in the head 22, and limited in its downward movement by a shoulder at the lower end of the socket.

The forming dies and the grippers are arranged in tandem order and are spaced apart to permit the interposition of the tab-forming portion of the strip between the dies and the grippers. Between the dies and grippers are located the punch dies and their adjuncts next described, for forming the prongs 28 and the oblique edges of the tabs 29. To the head 22 is fixed a block 44 (Figures 2, 5 and 6) having two downwardly projecting punch die sections 45 (Figures 9 and 11). Each section 45 has two end faces

46, forming a reentrant angle, their lower ends intersecting the bottom faces of the sections to form angular reentrant cutting edges 47 (Figure 9). To the base 12 is fixed 5 a block 48 containing openings 49 (Figures 10 and 12). The block is provided between the openings with a bar portion 48^a having vertical faces which intersect the top face of the bar portion to form salient cutting edges 10 50. The side walls of the openings 49 have recesses 51. A flat portion of the strip bears on the bar portion 48^a of the bed block 48 and is in the path of the moving punch die sections 45. When said sections descend, 15 their reentrant edges 47 cooperate with the salient edges 50 in forming the prongs 28, and bending the prongs downward into the recesses 51 as shown by Figure 6. The head 22 is provided with a presser 53, which is 20 hexagonal in cross section, and is located between the reciprocating die sections 45 and normally projected below said sections by a spring 54, to an extent determined by the bearing of a head 55 on the presser, on a 25 shoulder at the lower end of a socket 56 (Figure 2) containing the spring and head. The presser clamps the flat tab-forming portion of the strip firmly against the upper end of the cross bar 48^a, while the cutting edges 30 47 and 50 are forming the prongs.

At the beginning of the operation, the strip is inserted until its advancing end projects between the punch dies, but does not project between the grippers. The machine is then operated to cause the formation of the first curved portion by the forming dies, and a pair of prongs at the leading end of the strip, there being a short surplus end on the strip which is subsequently removed by the shearing cutters hereinafter described.

The presser 53 cooperates with the fixed bar portion 48^a in confining the strip until the prongs have been formed. When the head 22 rises, the strip is fed forward until the formed portion is between the grippers 30 and 31, and the flat leading end portion of the strip is between a movable shearing cutter 58 (Figure 2) fixed to the head 22, 45 and a fixed shearing cutter 57 fixed to the bed plate 12.

The strip is raised from the lower forming die 15 when the head 22 rises by a lifting pin 58 movable in a socket in the block 48, 55 and a pair of lifting pins 59 movable in sockets in the lower forming die 15, said pins bearing on the under side of the strip and being pressed upwardly by springs 60, their upward movement being limited by the 60 contact of heads on their lower ends with shoulders at the upper ends of the sockets.

The strip is fed intermittently into the machine by feed rolls 61 shown by dotted lines in Figure 2, the rolls being actuated by 65 suitable mechanism (not shown) to feed the

strip a distance equal to the length of a completed stiffener when the head 22 is raised, and remaining at rest during the punching and forming operations.

After the first curved portion has been 70 formed by the forming dies, and moved forward and grasped by the grippers, the next curved portion is formed.

The next feeding movement causes the 75 leading end portion of the strip to project from the rear end of the machine, said portion now requiring only severance from the strip to convert it into a complete shank stiffener.

The strip is now so positioned that the 80 shearing cutters sever it on the line *v v* (Figure 7), a completed stiffener formed as shown by Figure 8 being thus produced.

To prevent edgewise displacement of the strip in its passage through the machine, I 85 provide edge guides composed of plates 63, having slots 64, slightly wider than the strip, and arranged so that their edges prevent edgewise movement of the strip from its predetermined path. There are preferably 90 three of these plates, one located at the receiving end, another at the delivering end, and the third midway between said ends, as shown by Figure 2, the plates being secured to fixed parts of the machine. 95

It will be seen that the fixed die block 48 and the reciprocating die block 44 constitute elements of a pronging mechanism adapted to simultaneously cut two spaced apart pairs of oblique slits extending inward from the opposite edges of a flat tab-forming portion 27 of the strip, and thereby form the inner edges of two pairs of prongs located at opposite edges of the tab-forming portion and to simultaneously bend the prongs to their operative positions, the bases of the prongs being spaced apart so that when the tab-forming portion is transversely severed at *v v*, tabs 29 are formed which project outward from the prongs. 100 105

The cutting edges which slit the strip to partially sever the prongs therefrom, are arranged to impart a tack-like form to the prongs enabling the same to be easily driven, each prong being very narrow at its base portion and tapering therefrom to its point. 110

The strip lifting pins and the strip edge guides may be employed in a machine which does not include the grippers 30 and 31, as shown by my co-pending application 115 Serial No. 42,455, filed July 9, 1925.

I claim:

1. A shank stiffener machine comprising a fixed base; a reciprocating head movable toward and from the base; a pair of forming dies including a lower die fixed to the base and an upper die fixed to the head, said dies being formed to longitudinally curve and emboss a portion of an elongated strip interposed therebetween; a pair of yielding 125 130

grippers including a lower gripper yieldingly connected with the base and an upper gripper yieldingly connected with the head, said grippers being formed to grip a formed 5 strip portion; the forming dies and grippers being spaced apart to permit the interposition of a tab-forming portion of the strip therebetween; pronging mechanism interposed between the forming and gripping dies, said mechanism including means for simultaneously cutting two spaced apart pairs of oblique slits extending inward from the opposite edges of the tab-forming portion of the strip, and thereby forming the 10 inner edges of two pairs of prongs located at opposite edges of said tab forming portion, and means for simultaneously bending the prongs to their operative positions; and cutters adapted to transversely sever the tab 15 forming portion and convert the same into two tabs projecting outward from the prongs.

2. A shank stiffener machine comprising a fixed base, a reciprocating head movable 20 toward and from the base; a pair of forming dies including a lower die fixed to the base and an upper die fixed to the head, said dies being formed to longitudinally curve and emboss a portion of an elongated strip interposed therebetween; a pair of yielding grippers including a lower gripper yieldingly connected with the base and an upper gripper yieldingly connected with the head, said 25 grippers being formed to grip a strip portion formed by the forming dies, the forming dies and grippers being spaced apart to permit the interposition of a tab-forming portion of the strip therebetween; pronging mechanism interposed between the forming 30 dies and the grippers, arranged to act on said tab-forming portion, said mechanism including a reciprocating die block fixed to the head and provided with a pair of punch die sections having reentrant cutting edges, and a die block fixed to the base and provided with openings formed to receive the reciprocating sections and with a bar portion having salient cutting 35 edges cooperating with the reentrant edges of the reciprocating sections, said openings having recesses formed to cooperate with the reciprocating sections in simultaneously bending two pairs of prongs from the tab-forming portion of the strip; and a spring-actuated presser movably supported by the head and adapted to clamp the tab-forming portion of the strip against the bar portion of the fixed die block. 40

3. A shank stiffener machine comprising a fixed base; a reciprocating head movable toward and from the base; a pair of forming dies including a lower die fixed to the base and an upper die fixed to the head, said dies being formed to longitudinally curve and emboss a portion of an elongated strip interposed therebetween; pronging mechanism at the inner end of the forming dies, said mechanism including means for cutting the strip to form the inner edges of a plurality of prongs, in opposite edges of the strip, and means for bending said prongs downward from the strip; spring-pressed 45 lifting pins bearing on the under side of the strip at opposite sides of the pronging mechanism and adapted to lift the prongs from the bending means of said mechanism, and permit a feed movement of the strip, and a plurality of fixed edge guides contacting with the opposite edges of the strip to prevent edgewise displacement of the latter, one of said guides being located at the forward end of the fixed forming die, and another between the inner end of the fixed forming die and the pronging mechanism. 50

5. A shank stiffener machine comprising a fixed base; a reciprocating head movable toward and from the base; a pair of forming dies including a lower die fixed to the base and an upper die fixed to the head, said 55 dies being formed to longitudinally curve and emboss a portion of an elongated strip interposed therebetween; a pair of yielding grippers including a lower gripper yieldingly connected with the base and an upper gripper yieldingly connected with the head, said grippers being formed to grip a strip portion formed by the forming dies, the forming dies and grippers being spaced apart to permit the interposition of a tab-forming portion of the strip therebetween; pronging mechanism interposed between the forming 60 dies and the grippers, and arranged to act on said tab-forming portion, said mechanism including a reciprocating die block fixed to the head and provided with a pair of punch die sections having reentrant cutting edges, and a die block fixed to the base and provided with openings formed to receive the reciprocating sections and with a bar portion having salient cutting edges cooperating with the reentrant edges of the reciprocating sections, said openings having recesses formed to cooperate with the reciprocating sections in simultaneously bending two pairs of prongs from the tab-forming portion of the strip; and a spring-pressed lifting pins bearing on the under side of the strip at opposite sides of the pronging mechanism and adapted to lift the prongs from the bending means of said mechanism, and permit a feed movement of the strip, and a plurality of fixed edge guides contacting with the opposite edges of the strip to prevent edgewise displacement of the latter, one of said guides being located at the forward end of the fixed forming die, and another between the inner end of the fixed forming die and the pronging mechanism. 65

In testimony whereof I have affixed my signature.

WILLIAM H. NICKERSON.
